AUXILIARY DYNAMOTOR FOR THE IGNITION SYSTEM OF AN INTERNAL COMBUSTION ENGINE

Stanley R. McClure, Rowena, Ky.

Continuation of abandoned application Ser. No. 836,299, Aug. 26, 1959. This application Mar. 15, 1963, Ser. No. 266,776

3 Claims. (Cl. 315—218)

This invention relates to an improved ignition apparatus for internal combustion engines.

This application is a continuation of my copending application Serial No. 836,299 for Ignition Apparatus filed August 26, 1959 which is a continuation in part of my co-pending application Serial No. 758,523 for Dynamo Compensator for D.C. Jump Spark Ignition, filed September 2, 1958, now abandoned, and of co-pending application Serial No. 835,521 filed August 24, 1959, for Ignition System, now 2,998,470.

It is well known that in the conventional ignition system ordinarily utilized in automotive vehicles that the time allowed for producing necessary spark varies inversely with the speed of the engine. Consequently at low speed the sparking interval is relatively long while at high speed it is relatively short. An inherent weakness in such a system is that spark current diminishes as the engine speed increases and at high speed decreases to such an extent that the effectiveness of the spark is seriously impaired. This phenomenon is termed "spark fade" and is due to reactance caused by the high frequency of spark required at high speed. This action occurs because magnetic flux can be built up in the core of the induction coil only during the intervals when the breaker points are closed. The time length of these intervals diminishes as the engine speed increases, and as a consequence the sparking interval at high speed is not sufficiently long to enable magnetism to be built up in the core of the induction coil to the same degree that it can in the longer interval available at lower engine speed. Thus when the engine is running at high speed the sparking interval is reduced to such an extent as to cause corresponding reduction of intensity and resultant inefficiency of the spark with a proportional decrease in the power of the engine.

An important object of the present invention is to provide a simple and automatic means for maintaining uniform sparking efficiency in the ignition circuit under varying conditions of speed of the engine than has heretofore been practiced.

Another important object of this invention is to provide a means for use with conventional battery ignition systems which provide a higher spark voltage as speed increases.

Still another object of this invention is to provide a compensating means for the conventional battery ignition system that at a predetermined speed will become stable in output.

Still another object of this invention is to provide a means for use with compensating means for a conventional battery ignition system which provides higher spark voltage upon starting the engine.

The difficulties referred to above, i.e., fading of spark voltage with increase in speed due to the reactance of the induction coil have been for the most part overcome by the use of the apparatus disclosed in my co-pending application, S.N. 758,523, previously referred to. This device in brief consisted of a small dynamo serially installed in the primary circuit of a conventional battery ignition system with its armature driven by the engine and its electromagnetic field furnished by a winding across the battery. Since the armature of the dynamo is driven at

2

a speed proportional to the speed of the engine the voltage produced is proportional to the speed of the engine. Thus as sparking frequency is increased due to high engine speed, the voltage is increased to compensate for increased reactance at the induction coil. At idling speeds an inconsequential amount of voltage is produced so that the system compensates automatically to variations in engine speed. It was found, however, that although this was an exemplary improvement over prior methods that at high engine speed the spark voltage was at times still erratic. It was determined that the erratic spark was due to reactance of the armature of the dynamo.

It was discovered that this defect could be eliminated by the installation of a relatively large condenser connected to the brushes of the auxiliary dynamo, or across the ignition source at a point between said dynamo and the spark coil. By relatively large it will be understood that the conventional condenser installed in close proximity to the contacts is of one-half to one microfarad in size. I have found, however, that the capacity of my auxiliary condenser attached at the points indicated above should be 100 to 800 times as great as the conventional condenser. The preferred capacity is in a range of from 200 to 400 microfarads. Larger condensers may be utilized and as a matter of fact I have utilized 500 and 600 microfarad condensers which operate quite efficiently but show no improvement over the 400 microfarad condensers.

The installation of the auxiliary dynamo and condenser causes an increase in resistance which under normal conditions of temperature is negligible. However, in extremely cold weather, this added resistance may cause difficulty in starting the motor since operation of the starter, in turning over the cold engine, consumes a very substantial percentage of the power output of the battery. This causes a severe drop in potential at the gaps of the spark plugs. For maximum starting efficiency, the spark plug potential should be at a maximum while the starter is in operation, since as is well known, the current required to turn over the engine in cold weather will quickly deplete the battery voltage. To compensate for this condition, one embodiment of my invention utilizes an armature of the auxiliary dynamo, comprising a core and two commutators, commonly termed a "dynamotor," in which one of the commutator brushes is connected by means of a switch to the battery. This commutator acts as a motor while the other commutator acts as a generator. The shaft of the armature which under normal conditions is driven by the engine, is connected to a clutch disengaged from the engine when it is not running. A suitable clutch might be an "overrunning" clutch of the ratchet or roller type. Thus, upon closing of the starter switch onto the switch connected to the brush of the motor commutator, voltage from the battery spins the armature to impress additional voltage upon the spark coil in order to provide a hot starting spark as the motor is turned over by the starter. This places a drain of about 5 or 6 amps. upon the battery, and at the same time produces a hot spark which allows almost instantaneous starting so that the overall drain on the battery is reduced.

The invention will be better understood by reference to the attached drawings.

Referring now to the drawings, FIG. 1 is a diagrammatic view of an electric ignition system embodying the various features of my invention.

FIG. 2 is a diagrammatic view of a portion of a similar system showing the condenser connected at a different point.

FIG. 3 is a diagrammatic view of a portion of a further modified system in which a second field winding of the auxiliary dynamo has been omitted.

FIG. 4 is a diagrammatical view of a specially modified armature attached to an "overrunning clutch."

Referring now to FIG. 1, the battery or direct current source is indicated by numeral 1. Connected to the battery are lines 2 and 3 and connected across lines 2 and 3 is first electromagnetic field winding 4. The electromagnetic field produced by this winding energizes the dynamo, the armature of which is designated by numeral 5 and the brushes of which are designated by numeral 19. Connected to the two brushes is a second field winding 6 which in one embodiment may be polarized to aid the first field winding 5. In this embodiment, i.e., field 6 polarized with field 4, the magnetic strength of field winding 6 varies in proportion to the speed of revolution of the armature 5 so as to increase the voltage impressed on the spark coil as the armature speed increases. Numeral 7 designates a shaft connected to any accessory engine shaft not shown. Numeral 20 designates a condenser connected to brushes 19 of the accessory dynamo. Numeral 23 designates a line connected to brush 19 and resistor 24 which leads to the primary of spark coil 12. Numeral 11 designates a one-half microfarad condenser conventionally connected across the points or contacts 9 and 10 near the primary of spark coil 12. Numeral 13 designates the iron core of spark coil and numeral 14 designates the secondary of spark coil. 15 designates the spark plug. 8 designates a cam and numeral 25 designates a spring utilized in conjunction with the breaker points. 16 designates the armature of the standard two brush generator, 17 designates the field winding of said generator and 18 designates a voltage regulator of the generator. 21 designates the ignition switch.

As previously indicated shaft 7 is a mechanical means which connects with the armature 5 of the accessory dynamo and an accessory engine driven shaft. This may be an extension of the shaft of the standard generator. The armature 5 of the accessory dynamo may be driven by a conventional V belt drive connected to an engine driven shaft so that the speed of the armature is in proportion to the speed of the engine. In this manner the output of the dynamo is proportional to the speed of the engine and the system automatically compensates to variation in engine speed. As previously indicated another embodiment of my invention which is shown in FIG. 1 involves second field winding 6 polarized in opposition to field winding 4. In this embodiment the magnetic strength of field winding 6 is essentially nil at zero r.p.m. whereas the magnetic strength produced by field winding 4 is essentially constant at all engine speeds deriving its strength from the battery. Increase in speed produces additional current until a predetermined speed is reached. This allows an increased spark at low speed so that full horsepower is available for the engine on hills and for fast acceleration. However, as speed is increased to a predetermined point magnetic field winding 6 in opposition to magnetic field winding 4 stabilizes the voltage. This effectively governs the maximum voltage of the system.

FIG. 2 is a modification of FIG. 1 showing the accessory condenser 20 connected at a different position. As previously indicated, this condenser is preferably of a capacity of 200 to 400 microfarads. However, larger condensers may be utilized if desired.

In FIG. 3 the second electromagnetic field winding 6 has been omitted. It will be noted that in FIG. 3 the condenser is connected in a position analogous to FIG. 1.

In operation the condenser 20 connected to the brushes of the auxiliary dynamo, or across the ignition source at a point between the brush 19 and the spark coil 12, as shown in the drawings, acts as a power reservoir and thereby prevents the armature of the accessory dynamo from being affected by the frequency of discharge caused by opening and closing of the breaker points at high engine speed. In effect, the condenser acts as a cushion to protect the armature from the constant high speed

discharge caused by the frequency of sparking, common with today's high horsepower engines.

Referring now to FIG. 4, 27 designates the shaft of the armature. Numerals 28 and 29 designate commutators and 30 designates the core of the armature. 22 designates the brushes of the motor commutator 28. Numeral 19 designates the brushes of generator commutator 29. Numeral 31 designates an "overrunning clutch" of the ratchet type which is attached to a shaft of the engine, not shown. Similarly, a roller clutch may be utilized instead of the ratchet clutch. A brush 22 of commutator 28 is connected by way of switch 35 and starter switch 32, to the battery 1. The starter motor is designated by numeral 33. Brush 19 of commutator 29 is connected by way of ignition switch 21 to battery 1. The corresponding brush 19 of commutator 29 is connected by line 23 to spark coil not shown. Field winding 4 connected between lines 2 and 3 produces a magnetic field which energizes the armature. In operation, upon closing of starter switch 32, onto switch 35, voltage from battery 1 is impressed upon motor commutator 28 via brush 22 and spins shaft 27, disengaged by clutch 31 from the driving means. The voltage produced by the revolution of the armature is carried by the line 23 to the primary of the spark coil, not shown, to produce a hot starting spark. Simultaneously, starter motor 33 turns over the engine to start the engine.

Upon starting of the engine, clutch 31 via driving means not shown, engages with shaft 27 to turn the armature to produce voltage proportional to the speed of the engine in the manner previously described. Simultaneously, switches 32 and 35 are opened and motor commutator 28 is disconnected from the circuit.

It is obvious that many modifications can be made from those shown in the illustrations. The output of the dynamo may be varied to produce an essentially stable spark at all engine speeds and alternately to produce an increased spark at increased engine speeds. The latter effect may be also achieved by the addition of the second field winding 6 when polarized to aid the first field winding 4. In another embodiment the second field winding 6 may be polarized in opposition to field winding 4 so as to allow increased spark at lower engine speeds while limiting the spark at high engine speed and thus governing the maximum voltage produced. I have found that the invention increases engine efficiency, and increases gas mileage.

It is evident that the system shown may be further modified from the scope of the invention, therefore I do not wish to limit the invention to the precise details herein illustrated and described.

I claim:

1. In an ignition system for use with a variable speed internal combustion engine which includes a battery and three parallel circuits across the terminals of the battery in which:
  - (a) The first circuit contains a generator;
  - (b) The second is an ignition circuit and contains an ignition switch, a spark coil having a primary winding which is electrically interconnected in said circuit and interrupting means for making and breaking the circuit;
  - (c) The third circuit is normally open and contains a starting motor and switch means for closing the circuit when the ignition switch is closed, means for providing a higher spark voltage upon starting and for increasing sparking efficiency under increased conditions of speed which comprises: an auxiliary dynamo serially installed in the ignition circuit between the battery and the spark coil, said dynamo comprising an engine-driven armature and magnetic means for providing a stable magnetic field for said dynamo, said armature comprising
- (a) A motor commutator and brushes in which one of

said brushes is electrically connected to said third circuit;

(b) A core;

(c) A generator commutator and the brushes in which one of said brushes is connected to the primary winding of said spark coil,

in combination with clutch means operatively connected to said armature and connectible to the engine so that said armature is disengaged from the engine and freely rotatable when the engine is not running.

2. In an ignition system for use with a variable speed internal combustion engine, which includes a battery and two parallel circuits across the terminals of the battery in which:

(a) The first circuit contains a generator;

(b) The second circuit is an ignition circuit and contains an ignition switch, a spark coil having a primary winding, which is electrically interconnected in said circuit, interrupting means for making and breaking the circuit and a first capacitor connected across said interrupting means,

means for providing increased sparking efficiency under conditions of increased engine speed which comprises:

(a) An auxiliary dynamo having brushes and an engine-driven armature, said auxiliary dynamo being 25 serially connected in the ignition circuit between the battery and the spark coil;

(b) Magnetic means for providing a stable magnetic field for said dynamo; and

(c) A second capacitor connected in shunt across the 30 brushes of said auxiliary dynamo, said second ca-

pacitor having a capacitance of greater than 150 microfarads.

3. In an ignition system for use with a variable speed internal combustion engine, which includes a battery and 5 two parallel circuits across the terminals of the battery in which:

(a) The first circuit contains a generator;

(b) The second circuit is an ignition circuit and contains an ignition switch, a spark coil having a primary winding which is electrically interconnected in said circuit, interrupting means for making and breaking the circuit and a first capacitor connected across said interrupting means,

means for providing increased sparking efficiency under 15 conditions of increased engine speed which comprises:

(a) An auxiliary dynamo having brushes and an engine-driven armature, said auxiliary dynamo being serially connected in the ignition circuit between the battery and the coil;

(b) Magnetic means for providing a stable magnetic field for said dynamo; and

(c) A second capacitor electrically interconnected in said circuit, across the battery, at a point between the auxiliary dynamo and the spark coil, said second capacitor having a capacitance of greater than 150 microfarads.
